UNITED STATES PATENT OFFICE

GOTTDANK L. KOTHNY, OF STRAFFORD, PENNSYLVANIA, ASSIGNOR TO C. H. WHEELER MANUFACTURING COMPANY, OF PHILADELPHIA, PENNSYLVANIA, A CORPORATION OF PENNSYLVANIA

FLUID-CONDENSING SYSTEM

Application filed October 23, 1926. Serial No. 143,567.

My invention relates to apparatus for condensing a fluid utilized for compressing another non-condensable fluid, and has particular reference to a fluid comprising steam and 5 air.

In accordance with my invention, there is utilized apparatus comprising a plurality of ejectors and a condenser shell containing a plurality of groups of tubes, one of 10 said ejectors discharging the fluid to be condensed through the tubes of one of said groups, the uncondensed fluid thereafter passing around the tubes of another of said groups through which a cooling medium is flowing, 15 to another ejector which further compresses the remaining uncondensed fluid and discharges the same through a third group of tubes, and simultaneously with the foregoing operation a cooling medium, as condensate, 20 is caused to circulate exteriorly of the first and third groups of tubes.

Further in accordance with my invention, the same condenser shell encloses all of the various groups of tubes and, further, said 25 shell comprises a member detachable therefrom and facing that group of tubes through which the cold water or other cooling medium flows to permit the passage of suitable cleaning apparatus through the tubes, and, more 30 particularly, facing each end of said group of tubes there is provided a member detachable from the shell to more readily facilitate the cleaning operation.

In U. S. Patents Nos. 1,536,539, 1,536,984 35 and 1,578,865 there is disclosed condenser structure wherein the steam and air mixture between the first and second stage ejectors passes interiorly of a group of tubes around which circulate a cooling medium. My invention, 40 while producing the same general result obtained in the arrangements disclosed in the aforesaid patents differentiates therefrom primarily because a cooling medium is passed through a group of tubes and the 45 steam and air mixture before passing to the second stage is caused to pass exteriorly of said last-named tubes.

My invention resides in the apparatus and 50 features of construction of the character hereinafter described and claimed.

For an understanding of my method and for an illustration of some of the various forms my apparatus may take, reference is to be had to the accompanying drawing in which:

55

Fig. 1 is a vertical sectional view of a condenser shell constructed in accordance with my invention.

60

Fig. 2 is a horizontal sectional view of the structure shown in Fig. 1.

Fig. 3 is another horizontal sectional view of the structure illustrated in Fig. 1, taken on a plane extending horizontally through the top end box.

65

Fig. 4 is a plan view of the structure shown in Fig. 1.

Fig. 5 is a vertical sectional view of a modified form of condenser shell and is taken on the line 5—5 of Fig. 6.

70

Fig. 5^a is a plan view of the structure shown in Fig. 5.

Fig. 6 is a horizontal view, partly in section and partly broken away of the structure illustrated in Fig. 5.

Fig. 10 is another horizontal sectional view of the structure illustrated in Fig. 8 taken through the upper end box.

95

Fig. 11 is a sectional view taken on line 11—11 of Fig. 8.

95

Referring to Figs. 1 and 4, at E there is illustrated the first stage ejector structure of any suitable character mounted upon the chest or box B of the condenser structure K, the chest B being divided by the partitions or

100

walls *a*, *b* and *c* into the four chambers *d*, *e*, *f* and *g*. These chambers have as a common wall the tube sheet or plate *h* held between the box *B* and one end of the shell *i* of the condenser structure *K*. The lower end of the shell *i* is closed by the plate or tube sheet *j*, which forms a wall or closure for the lower chest or box *B*¹ having the partition or wall *k* dividing it into the chambers *l* and *n*.

Within the shell *i* are the downwardly extending plates or baffles *o* and *p* whose lower ends are spaced from the tube sheet *j*. Suitably positioned between the aforesaid baffles *o* and *p* is the upwardly extending baffle or plate *q* whose upper end is spaced from the tube sheet *h*, these baffles or plates dividing the interior of the shell *i* into four passes in each of which is disposed a group of preferably vertical tubes *r*, only few tubes *r* being indicated in the drawing for the sake of clearness, it being understood that each group comprises any suitable number of tubes. The tubes *r* are of brass or other suitable material and may be secured by ferrules, not shown, or other well-known means, in the tube sheets *h* and *j*.

As clearly illustrated in Fig. 1, the first group of tubes *r* connects the chambers *g* and *n*; the second group connects the chambers *n* and *f*; the third group connects the chambers *e* and *l*; and the fourth group connects the chambers *l* and *d*.

The aforesaid first and second groups of tubes are those of a so-called "inter" condenser or interstage condenser, while the aforesaid third and fourth groups are those of a so-called "after" condenser. These "inter" and "after" condensers are disposed within the same condenser unit or shell *i*.

As illustrated in Fig. 3, the chamber *g* is formed in part by the oppositely disposed tube sheets or plates *s* and *t*, the former forming a wall or closure for the chest or box *B*² and the latter forming a similar wall or closure for the chest or box *B*³. Box *B*² is provided with a wall or partition *u* dividing it into the chambers *v* and *w* into each of which opens a fluid passage *x*. Secured in the tube sheets or plates *s* and *t* are a suitable number of tubes *z*, those at the left of partition *u*, Fig. 3, being in communication with chamber *v* and a passage *x*, and those at the right of said partition *u* being in communication with chamber *w* and the other passage *x*, all of said tubes at their other ends being directly in communication with the interior of box *B*³.

If desired, chamber *g* may be provided with the transverse plate or baffle *a*¹ utilizable for deflecting the mixture of air and vapors passing upwardly exteriorly of the tubes *z*.

The aforesaid ejector structure *E* is placed in communication with the chamber *f* by the tubular diffuser *b*¹, Fig. 1, and the chamber *g* is connected by a pipe, conduit or the like *C*¹

with the second stage ejector *E*¹, which delivers into the passage *d*.

The ejector *E* discharges a mixture of steam and air varying in ratio from one tenth to unity into the chamber *f* and thence downwardly through a group of tubes *r* of the "inter" condenser into the chamber *n*. While thus passing downwardly, nearly all of the steam is condensed and collects in the chamber *n* from which it may be withdrawn through the passage *d*¹. The air with the remaining uncondensed steam passes from chamber *n* through the group of tubes *r* leading to chamber *g*, further condensation of the steam meanwhile occurring until finally the remaining air and vapors enter the chamber *g* and pass exteriorly of tubes *z*.

Simultaneously with the foregoing operation, condensate, fresh water, or other cooling medium is supplied to the "inter" condenser by way of passage *e*¹ and circulates exteriorly of the first group of tubes *r*, then around the baffle *p*, and then exteriorly of the second group of tubes *r*. After passing around the baffle *q*, the condensate circulates exteriorly of the two groups of tubes of the "after" condenser and emerges by way of passage *f*¹.

At the same time, cold water, preferably from a separate source, is supplied to a passage *w* from whence it flows through a group of tubes *z* on one side of partition *u* into the box *B*³, thence into and through in reverse direction the group of tubes on the other side of said partition *u* and finally emerges through the other passage *w* in end box *B*².

The remaining air and vapor mixture leaves the cold pass condenser or chamber *g* by way of conduit *C*¹ and passes to ejector *E*¹ where further compression to atmospheric pressure, more or less, is effected, whereupon the mixture is discharged to the chamber *d*, thence through a group of tubes *r* of the "after" condenser to the chamber *l* from which the condensed steam may be withdrawn through passage *g*¹. From chamber *l*, the mixture passes upwardly through the other group of tubes *r* of the "after" condenser to chamber *e* and thence by way of passage *h*¹, Fig. 4, which delivers into the atmosphere or into any suitable chamber or region at a pressure equal to atmospheric or either greater or less than atmospheric pressure.

The temperature of the water passing through the tubes *z* usually is from ten to twenty-five degrees lower than that of the condensate circulating exteriorly of the tubes *r* and, therefore, condensation of the vapors results when they pass exteriorly of said tubes *z*. The circulating cooling water, however, is often impure and, therefore, this part of the apparatus may be closed down merely by shutting off the water supply and the tubes *z* cleaned of impurities. To thus render the tubes *z* functionless does not destroy the operability of the apparatus as a whole, for

under such circumstances, the vapor mixture passes exteriorly of said tubes as usual, although, due to the absence of a cooling medium therewithin, the capacity of the apparatus as a whole is somewhat reduced due to the fact that the temperature of the mixture reaching the second stage ejector E^1 is somewhat higher than when the cold pass condenser is in operation. This type of condensing structure is probably not as effective for condensing an air and vapor mixture as that illustrated in the aforesaid patents. However, this is more than offset because in the prior art constructions, as exemplified in said patents, the cold water passes exteriorly of the tubes, while with my invention the cold water passes interiorly of the tubes. In the first case the cleaning operation is extremely difficult, while in the latter it is a simple operation.

Referring to Figs. 5, 5^a, 6, 7, 7^a and 7^b, there is illustrated an arrangement somewhat similar to that described above with the exception that two radiojets are arranged on one combined "inter" and "after" condenser with the cold pass condenser arranged inside of the combined after condenser instead of in the upper heads.

In Fig. 5, at E^4 there is illustrated the first stage ejector structure of any suitable character, for example, as illustrated in said U. S. Letters Patent No. 1,535,137, the ejector structure being mounted upon the chest or box B^4 disposed upon the tube sheet a^4 held between the box B^4 and one end of the shells b^4 and c^4 of the condenser structure K^4 .

The lower end of shells b^4 and c^4 is closed by the plate or tube sheet d^4 , which forms a wall or closure for the lower chest or box C^4 .

As illustrated in Figs. 7 and 7^a, the portion of box B^4 overlying the shell b^4 is divided by the partitions or walls e^4 , f^4 and g^4 into the four chambers h^4 , i^4 , j^4 and k^4 . Also, the portion of box C^4 which underlies the shell b^4 is divided by the partitions or walls l^4 and m^4 into the three chambers n^4 , o^4 and p^4 .

Within the shell b^4 is the downwardly extending plate or baffle q^4 whose lower end is spaced from the tube sheet d^4 . On each side of the aforesaid plate or baffle are disposed the groups of preferably vertical tubes u^4 , only few tubes u^4 being indicated in the drawing for the sake of clearness. As described above with respect to the tubes r of Figs. 1-4, the tubes u^4 may be of brass or other suitable material and may be secured in any suitable manner, as by ferrules, not shown, in the tube sheets a^4 and d^4 .

As clearly illustrated in Fig. 7, the first group of tubes u^4 connects the chambers h^4 and p^4 ; the second group connects the chambers p^4 and j^4 ; the third group connects the chambers i^4 and o^4 ; the fourth group connects the chambers o^4 and h^4 ; and the fifth group connects the chambers h^4 and n^4 .

The aforesaid first and second groups of tubes are those of a so-called "after" condenser, while the aforesaid third, fourth and fifth groups are those of a so-called "inter" condenser or interstage condenser. These "inter" and "after" condensers are disposed within the same shell b^4 .

As illustrated in Figs. 5 and 6, the aforesaid shells b^4 and c^4 in conjunction with the tube sheets a^4 and d^4 define an interior space which is entirely closed by the oppositely disposed walls or tube sheets v^4 and w^4 supporting the tubes x^4 , preferably divided into a plurality of groups by the oppositely extending baffles or plates y^4 . Extending vertically within the interior space and dividing the same into two compartments is the wall J engaging at its respective upper and lower ends the tube sheets a^4 and d^4 . Suitably secured to the respective tube sheets v^4 and w^4 are the boxes b^5 and b^6 , the former comprising the single partition or wall c^5 and the latter comprising the two spaced partitions or walls d^5 and e^5 . Box b^5 is provided with the orifice or opening f^5 through which cold water or other cooling medium is admitted to the topmost group of tubes x^4 , Fig. 5, and thereafter circulates, due to the walls c^5 , e^5 and d^5 , in series through the remaining groups of said tubes x^4 and finally emerges by way of orifice g^5 in box b^5 .

Condensate or other cooling medium is supplied by way of passage h^5 to the "inter" condenser and passes exteriorly of the several groups of tubes u^4 in a circuitous path due to the baffle q^4 , the condensate finally emerging through the passage i^5 .

Simultaneously, the ejector E^4 functions as well understood in the art to discharge steam and air into the chamber i^4 , from which the mixture passes downwardly through a group of tubes u^4 into the chamber o^4 . By such action substantial condensation of the steam occurs, the condensate collecting in said chamber o^4 passing through passage j^5 to chamber n^4 and thence to a suitable destination by way of conduit k^5 . The air with the remaining uncondensed steam passes upwardly from chamber o^4 through a group of tubes u^4 to chamber h^4 , thence downwardly through another group of tubes u^4 to chamber n^4 from which any additional condensate passes by way of conduit k^5 .

Chamber n^4 is in communication by passage l^5 , in tube sheet d^4 , Figs. 5 and 7^b, with the chamber containing the cold water tubes x^4 and, accordingly, the air and condensed steam pass through said chamber exteriorly of said tubes x^4 along a circuitous path and finally pass through a passage m^5 , in tube sheet a^4 , Figs. 5 and 7^a, into a chamber n^5 in box B^4 .

From chamber n^5 the mixture passes through conduit o^5 to the second stage ejector E^5 of any suitable character; for example, as

disclosed in said U. S. Patent No. 1,535,137. In the ejector E^6 further compression is effected, whereupon the mixture is discharged to the chamber h^4 , Fig. 7, thence through a group of tubes u^4 to the chamber p^4 from which any condensate may be withdrawn through conduit p^5 . Thereafter, the mixture passes upwardly through another group of tubes u^4 to the chamber j^4 provided with a passage q^5 opening into the atmosphere or into any suitable chamber, usually at atmospheric pressure.

In accordance with the form of my invention illustrated in Figs. 5, 6, 7, 7^a and 7^b, the shell c^4 and the structure therewithin are duplicates, respectively, of shell b^4 and the structure enclosed thereby.

Condensate is supplied exteriorly of the tubes u^4 of shell c^4 by way of conduit s^5 , preferably branching from conduit h^5 and emerges from said shell by way of conduit t^5 preferably connected with conduit i^5 .

The end box C^4 is provided with a transverse wall J^1 , Fig. 7^b, which may be a continuation of wall J but preferably is a separate wall formed integrally with said end box C^4 and extends upwardly into contact with the tube sheet d^4 . As a result commingling of the respective mixtures of the twin condensers in the end box C^4 is prevented while, as stated above, the wall J prevents commingling of the mixtures in the pass occupied by the cold water tubes. Eventually, each mixture passes separately into a chamber n^5 and thence to the suction of the second stage ejector. The groups of tubes last traversed by the two mixtures communicate with the single chamber j^4 extending above each of the shells b^4 and c^4 , Fig. 7^a.

Referring to Figs. 8, 8^a, 9, 10, and 11, there is illustrated a form of my invention wherein all of the various groups of tubes are arranged vertically and enclosed within a single condenser shell.

To this end, there is provided a shell A^6 whose upper and lower ends are closed by the boxes B^6 and C^6 . Between the flanged extremity of box B^6 and the upper end of shell A^6 is disposed a tube sheet a^6 and between the flanged extremity of box C^6 and the lower end of said shell is disposed a similar tube sheet b^6 .

As illustrated in Fig. 10, the box B^6 is traversed by the substantially diametrical wall c^6 and one of the compartments thus formed is subdivided into the chambers d^6 , e^6 , f^6 and g^6 by the walls or partitions h^6 , i^6 and j^6 . Opening, respectively, into the aforesaid chambers d^6 , e^6 , f^6 and g^6 are the tube groups k^6 , l^6 , m^6 and n^6 , each group comprising any suitable number of tubes and the individual tubes being constructed of any suitable material, preferably, however, of brass. At their lower ends, the tubes of group k^6 are in communication with those of group l^6

and the tubes of group m^6 communicate with those of group n^6 . However, communication between group k^6 and l^6 on the one hand and group m^6 and n^6 on the other hand is prevented by a wall c^8 , dividing the box C^6 into two chambers into one of which opens the aforesaid groups of tubes k^6 and l^6 and into the other of which opens the groups of tubes m^6 and n^6 .

The other compartment formed by the aforesaid wall c^8 is divided into a plurality of chambers o^6 , p^6 , q^6 , r^6 , s^6 and t^6 by the walls or partitions a^7 , b^7 , c^7 , d^7 and e^7 . Opening into the chamber p^6 is the group of tubes f^7 . Opening into the chamber q^6 are the groups of tubes g^7 and h^7 while into chamber r^6 opens the similar groups of tubes i^7 and j^7 . Chamber s^6 corresponds with chamber p^6 and hence but one group of tubes k^7 opens thereto.

Box C^6 is provided with a diametrical wall c^9 , but corresponding generally with wall c^8 in box B^6 . The compartment thus formed is divided into a plurality of chambers by walls a^8 , b^8 , c^8 , d^8 , into one of which chambers opens the tube groups k^7 and j^7 , while in another opens the tube groups i^7 and h^7 , while in still another the tube groups g^7 and f^7 open.

Accordingly, cold water or other cooling medium entering the condenser shell through the passage l^7 passes downwardly through tubes k^7 , upwardly through tubes j^7 , downwardly through tubes i^7 , upwardly through tubes h^7 , downwardly through tubes g^7 , upwardly through tubes f^7 , and thence from the condenser shell by way of passage m^7 .

The shell A^6 of the condenser is also divided into two compartments by the substantially diametrical wall or partition n^7 , Fig. 9, in one of which compartments are received the aforesaid groups of tubes f^7 , g^7 , etc., traversed by cold water or the like, while the other compartment receives the groups of tubes k^6 , l^6 , etc.

Condensate enters the last-named compartment by way of passage o^7 , flows around the tubes k^6 , l^6 , m^6 and n^6 , preferably along a circuitous path by baffles or plates and emerges by way of passage p^7 .

The ejector E^6 of any suitable type, for example, as disclosed in the aforesaid U. S. Patent No. 1,535,137, simultaneously with the passage of condensate around the tube groups k^6 , l^6 , etc., and the passage of cold water through the tube groups f^7 , g^7 , etc., discharges steam and air through passage q^7 into chamber e^6 , Fig. 10, from whence the mixture passes downwardly through tubes l^6 into the chamber in box C^6 from which any condensate may be withdrawn through a conduit, not shown. The remaining mixture passes upwardly through tubes k^6 and thence into the chamber o^6 which communicates through an opening in the tube plate a^6 with the compartment containing the tube groups f^7 , g^7 . From this compartment the mixture of air

and remaining steam passes exteriorly of the tube groups f^7, g^7, h^7, i^7, j^7 and k^7 , preferably in a circuitous path under the influence of baffles, shown in Fig. 9, and finally passes upwardly through a passage in tube sheet a^6 into the chamber t^6 connected by a conduit q^8 with the suction of the second stage ejector E^7 of any suitable character but preferably of the character disclosed in the aforesaid U. S. Letters Patent 1,535,137.

10 In the ejector E^7 further compression of the mixture occurs and thereafter the same is discharged into chamber g^6 from which it passes through tubes n^6 into the chamber in box C^6 from which any condensate may be withdrawn through a conduit, not shown. From the aforesaid chamber in box C^6 , the mixture passes upwardly through tubes m^6 and then through a suitable vent, shown in dotted line in Fig. 10, leading preferably to the atmosphere.

15 Referring to Fig. 10, the chambers p^6, q^6, r^6 and s^6 are covered or closed by a plate-like cover r^8 , Fig. 8, and the chambers in the box C^6 into which open the tube groups f^7, g^7, h^7, i^7, j^7 and k^7 are closed by a similar cover r^8 .

20 Heretofore, when the steam and air mixture did not pass directly from the "inter" condenser to the suction of the second stage ejector, such mixture has been caused to pass through a group of tubes around which the cooling medium circulates. Under such circumstances, particularly when the cooling medium consists of dirty water or water containing impurities, as mud, alkaline matter, etc., these tubes within a short time become encrusted or encased with foreign matter which largely impedes the rapidity of heat transfer from the steam and air mixture, thereby seriously affecting the efficiency of the apparatus. Moreover, since such foreign matter accumulates exteriorly of the tubes, the removal thereof is an expensive and tedious operation, necessitating the closing down 40 of the entire apparatus.

45 In contra-distinction by my invention, any foreign matter in the cold water or other cooling medium is deposited interiorly of the tubes thereby rendering it a relatively simple matter to clean the same. Moreover, during the brief cleaning period that is required, the apparatus may be still kept in service, although, as stated above, at such time the efficiency of the system may be reduced.

50 Obviously, in Fig. 3, the end boxes B^2 and B^3 , and in Fig. 5, the end boxes a^5 and b^5 may be readily removed preparatory to cleaning the cold water tubes. Likewise, with respect to the construction illustrated in Figs. 8 to 11, the plates closing the ends of the shell above 55 and below the cold water tubes may readily be removed to permit the introduction of the tube cleaning apparatus.

55 It shall be understood that my invention is not limited to ejector apparatus of the two-

stage type, but that the principles and features thereof may be employed in connection with apparatus utilizing three or more stages, particularly if a cold pass is used for cooling the air vapor mixture leaving the "inter" condenser.

70 What I claim is:

1. In a fluid-condensing system utilizing an ejector, a condenser shell, a plurality of groups of tubes in said shell, the tubes of one of said groups communicating with the discharge of said ejector and passing the fluid to be condensed into a region around the tubes of another of said groups, and means for passing a cooling medium through the tubes of said last-named group.

75 2. In a fluid-condensing system utilizing a plurality of ejectors, a condenser shell, a first group of tubes in said shell through which one of said ejectors discharges the fluid to be condensed, a second group of tubes in said shell, means for passing a cooling medium through the tubes of said second group, and means for passing the fluid into the space around said second group of tubes.

80 3. In a fluid-condensing system utilizing a plurality of ejectors, a condenser shell, a first group of tubes in said shell through which one of said ejectors discharges the fluid to be condensed, a second group of tubes in said shell, means for passing a cooling medium through the tubes of said second group, means for passing the fluid into the space around said second group of tubes and thence to another of said ejectors, and a third group of tubes through which said last-named ejector discharges.

85 4. In a fluid-condensing system utilizing a plurality of ejectors, a condenser shell, a first group of tubes in said shell through which one of said ejectors discharges the fluid to be condensed, a second group of tubes in said shell, means for passing a cooling medium through the tubes of said second group, means for passing the fluid into the space around said second group of tubes and thence to another of said ejectors, a third group of tubes through which said last-named ejector discharges, and means for passing another cooling medium around the tubes of said first and third groups.

90 5. In a fluid-condensing system utilizing a plurality of ejectors, a condenser shell, a group of tubes in said shell through which one of said ejectors discharges the fluid to be condensed, a connection between said tubes and the suction of another of said ejectors, and a group of tubes through which a cooling medium flows interposed in said connection.

95 6. In a fluid-condensing system utilizing an ejector, a condenser shell, a plurality of groups of vertical tubes in said shell, the tubes of one of said groups communicating with the discharge of said ejector and passing

10

the fluid to be condensed into the region around the tubes of another of said groups, and means for passing a cooling medium through the tubes of said last-named group.

5 7. In a fluid-condensing system utilizing an ejector, a condenser shell, a plurality of groups of vertical tubes in said shell, the tubes of one of said groups communicating with the discharge of said ejector and passing the fluid to be condensed into the region around the tubes of another of said groups, and means for passing a cooling medium in 10 one direction through some of the tubes of said last-named group and in reverse direction through other tubes of said last-named group.

20 8. In a fluid-condensing system utilizing a plurality of ejectors, a condenser shell, a first group of vertical tubes in said shell through which one of said ejectors discharges the fluid to be condensed, a second group of tubes in said shell, means for passing a cooling medium through tubes of said second group, and means for passing the fluid into the space 25 around said second group of tubes.

30 9. In a fluid-condensing system utilizing a plurality of ejectors, a condenser shell, a first group of vertical tubes in said shell through which one of said ejectors discharges the fluid to be condensed, a second group of vertical tubes in said shell, means for passing a cooling medium through tubes of said second group, and means for passing the fluid into the space around said second 35 group of tubes.

40 10. In a fluid-condensing system utilizing a plurality of ejectors, a condenser shell, a first group of vertical tubes in said shell through which one of said ejectors discharges the fluid to be condensed, a second group of vertical tubes in said shell, means for passing a cooling medium through the tubes of said second group, means for passing the fluid into the space around said second group of tubes and thence to another of said ejectors, a third group of vertical tubes through which said last-named ejector discharges, and means for passing another cooling medium around the tubes of said first and third groups.

45 11. A condenser unit comprising a shell, a plurality of groups of tubes in said shell, means for passing the fluid to be condensed first through the tubes of one of said groups and then around the tubes of another of said groups, and means for passing a cooling medium through the tubes of said last-named group comprising a member which upon removal from the condenser shell permits access to the interior of said last-named tubes.

55 12. A condenser unit comprising a shell and a member detachable therefrom, a group of tubes in said shell, means for passing the fluid to be condensed through said tubes, and a second group of tubes in said shell through 60 which a cooling medium flows and around

which the fluid passes, said second group of tubes only facing said detachable member.

13. A condenser unit comprising a shell and a member detachable therefrom, a group of tubes in said shell, means for passing the fluid to be condensed through said tubes, and a second group of tubes in the shell facing said detachable member and around which the fluid passes, and means comprising said detachable member for passing a cooling medium through only said second group of tubes.

14. A condenser unit comprising a shell and a member detachable therefrom, a group of vertical tubes in said shell, means for passing the fluid to be condensed first through said tubes, and a second group of vertical tubes in said shell through which a cooling medium flows and around which the fluid passes, said second group of tubes only facing said detachable member.

15. In a fluid-condensing system utilizing a plurality of ejectors, a condenser shell, a vertical wall dividing said shell into a plurality of compartments, groups of vertical tubes in one of said compartments through which said ejectors discharge the fluid to be condensed, and groups of vertical tubes in another of said compartments around which said mixture passes and through which a cooling medium circulates.

16. In a fluid-condensing system utilizing a plurality of ejectors, a condenser shell, a vertical wall dividing said shell into a plurality of compartments, groups of vertical tubes in one of said compartments through which said ejectors discharge the fluid to be condensed, and groups of vertical tubes in another of said compartments through which a cooling medium circulates and around which said fluid passes while traveling between successive ejectors.

GOTTDANK L. KOTHNY.

CERTIFICATE OF CORRECTION.

Patent No. 1,757,723.

Granted May 6, 1930, to

GOTTDANK L. KOTHNY.

It is hereby certified that error appears in the printed specification of the above numbered patent requiring correction as follows: Page 5, line 16, strike out the word "not" and after the word "shown" same line insert the words and numeral in dotted line in Fig. 10.; same page, lines 19 and 20, strike out the words "shown in dotted line in Fig. 10," and insert instead the words and comma not shown,; and that the said Letters Patent should be read with these corrections therein that the same may conform to the record of the case in the Patent Office.

Signed and sealed this 2nd day of September, A. D. 1930.

(Seal)

**M. J. Moore,
Acting Commissioner of Patents.**
